UNITED STATES PATENT OFFICE

140,745

DESIGN FOR A SCABBARD OR THE LIKE

William E. Fairbairn, Washington, D. C., Fernleigh R. Graninger, Takoma Park, Md., and Earl G. Millison, Falls Church, Va.

Application October 13, 1944, Serial No. 115,750

Term of patent 7 years

(Cl. D22—6)

To all whom it may concern:

Be it known that we, William E. Fairbairn, a subject of the King of Great Britain, and Fernleigh R. Graninger and Earl G. Millison, citizens of the United States of America and residents of Washington, in the District of Columbia; Takoma Park, Maryland; and Falls Church, Virginia, respectively, have invented a new, original, and ornamental Design for a Scabbard or the like, of which the following is a specification, reference being had to the accompanying drawing, forming part thereof.

Fig. 1 is a top perspective view of a scabbard or the like, showing our new design;

Fig. 2 is a top plan view thereof;

Fig. 3 is a side elevational view thereof;

Fig. 4 is a bottom perspective view thereof; and

Fig. 5 is a bottom plan view thereof.

We claim:

The ornamental design for a scabbard or the like, as shown.

WILLIAM E. FAIRBAIRN.
FERNLEIGH R. GRANINGER.
EARL G. MILLISON.
